DOUBLE CASING PUMP

Aladar Hollander, Berkeley, Calif., assignor to
Byron Jackson Co., Berkeley, Calif., a corpora-
tion of Delaware

Application June 6, 1933, Serial No. 674,484

2 Claims. (Cl. 103—108)

This invention relates to double casing pumps, particularly multi-stage centrifugal pumps.

One of the objects of this invention is to provide simple and effective means for mounting the inner pump casing within the outer casing of a double casing pump.

A further object is to provide means for sealing the joint formed between the inner and outer casings adjacent the inlet ends thereof for effectively preventing the high pressure fluid contained in the space formed between the casings from leaking into the fluid inlet passages thereof.

A further object is to provide means for supporting the distal end of the inner casing upon the removable cover of the outer casing and for providing resilient packing means between the removable cover and the adjacent end of the inner casing.

A further object is to provide means readily accessible for bolting the inner casing to the outer casing.

A further object is to provide the outer casing with means for centering and slidably supporting therein each end of an inner casing and for providing a resilient gasket means acting between the casings at one end for retaining the other end thereof in effective sealing engagement and for providing means for preventing rotation of the inner casing.

Other objects and advantages of the invention will become apparent as the nature of the same is more fully understood from the following description and accompanying drawing, wherein is set forth what is now considered to be a preferred embodiment. It should be understood, however, that this particular embodiment of the invention is chosen principally for the purpose of exemplification, and that variations therefrom in details of construction or arrangement of parts may accordingly be effected and yet remain within the spirit and scope of the invention, as the same is set forth in the appended claims.

In the drawing:

The single figure illustrates a longitudinal sectional view of a double casing multi-stage centrifugal pump having a different arrangement of the means for mounting and sealing the inner casing therein.

The double casing centrifugal pump shown in the drawing may include an inner casing 50 mounted within an outer casing 51. The outer casing may be provided with a flange 52 adjacent its open end, which flanged portion may be counter-bored as at 53 to receive a plurality of lugs 54, which lugs may be bolted to the outer casing, as by

suitable screw means 55. If desired, the lugs may be recessed for setting the screw heads into the lugs. The face of the outer casing flange 52 may be stepped as at 56, while the face of the cover flange 57 may have a complementary stepped portion 58 and an annular gasket 59 may be mounted between the stepped portions of the outer casing and cover flanges while these flanges may be firmly clamped together as by suitable bolt means 60.

The inner casing 50 may be centered and supported at its fluid inlet end by the outer casing diaphragm 61 as by means of the axially cylindrical flange 62 of the inner casing slidably fitting into the bore 62a of the diaphragm; and to provide an effective fluid seal, a resilient gasket 61a may be positioned between the fluid inlet end of the inner casing and the diaphragm, thereby permitting a relatively longitudinal motion between the two casings to compensate for differences in degree of expansion of the cases. The resilient gasket may be placed under an initial compression as the inner casing is bolted into position so that a separating movement of the cases at this end may be effectively compensated for by the expansion of the resilient gasket. The resilient gasket will effectively seal the high pressure fluid space 63 from the fluid inlet channel 64.

The cover end of the inner casing may be supported and centered by an axially concentric boss 65, which boss may be suitably mounted upon and formed integral with the cover 66 while that end of the inner casing may be provided with a concentric bore 67 of appropriate diameter so as to nicely fit onto the cover boss 65. The cover end of the casing may be effectively sealed by placing a resilient annular gasket 68 upon the cover boss 65 and of sufficient size to be initially compressed during the clamping of the cover into operative position by the bolt means 60.

By this arrangement, the inner casing may expand freely longitudinally in both directions from the retaining lugs 54, and yet due to the two resilient gaskets, the ends thereof will remain effectively sealed to the outer casing diaphragm and cover respectively, irrespective of the relative movement between the casings.

The cover end of the pump may be provided with a standard form of stuffing box having an adjusting means 68, a shaft bearing 69, and a thrust bearing 69a. The number of pumping stages included within the inner casing may be of such number and type as to best meet the particular requirement for which the pump is desired to fulfill. The inner casing may be provided with an inlet passage 70 arranged to com-

municate with the inlet channel 64 of the outer casing, while a discharge passage 71 of the inner casing may communicate with the space 63 formed between the two casings. The outer casing may 5 be provided with a discharge nozzle having a discharge passage 73 for communicating the space 63 with the exterior of the pump. One of the principal features of this invention is the location of the lugs 54 and bolts 55 by which means 10 the inner casing is secured to the outer casing in such a manner as to minimize the effect of expansion strains between the inner and outer casings while providing accessibility for assembling and disassembling the pump. The lugs 54 also perform a further valuable service in maintaining 15 the inner casing correctly mounted within the space 63 of the outer casing when the cover 66 of the outer casing has been removed.

Having fully described the invention, it is to be 20 understood that it is not to be limited to the details herein set forth, but the invention is of the full scope of the appended claims.

I claim:

1. In a centrifugal pump, an outer casing open 25 at one end and having a fluid inlet at the other end, an inner cylindrical casing of substantially uniform external diameter mounted therein in circumferentially spaced relation thereto, a removable cup-shaped cover for the open end of 30 said outer casing, said inner casing having a fluid inlet passage communicating with the outer casing fluid inlet and a discharge passage commun-

cating with the space between said casings, said outer casing having a discharge nozzle communicating with said space, impeller means operatively mounted within said inner casing, said inner casing having a means formed intermediate the ends of the uniform cylindrical portion arranged to be bolted to the outer casing adjacent the outer end thereof, resilient packing means between said casings adjacent said fluid inlet, and resilient sealing means between said inner casing and the removable cover.

2. In a centrifugal pump, an outer casing open at one end and having a fluid inlet at the other end, an inner cylindrical casing of substantially uniform external diameter mounted therein in circumferentially spaced relation thereto, outwardly extending lugs carried by the inner casing intermediate the ends of the uniform cylindrical portion thereof, means for securing the said lugs rigidly to the outer casing at the open end thereof, a removable end cover for the open end of said outer casing, said inner casing having a fluid inlet passage communicating with the outer casing fluid inlet, a discharge passage communicating with the space between the casings, said outer casing having a discharge nozzle communicating with said space, impeller means operatively mounted within said inner casing, and a resilient packing means between said casings adjacent said inlets.

ALADAR HOLLANDER.
